APPARATUS FOR DEVELOPING COPIES

Sven Erik Johannes Hellsten, Malmo, Sweden

Application November 20, 1951, Serial No. 257,379

5 Claims. (Cl. 95—89)

This invention relates to an apparatus for developing copies as exposed in light-copying or light-tracing apparatus, more particularly a developing apparatus of the type in which the casing comprises two stationary chambers one above the other, the upper chamber serving as the developing chamber and containing a bath of ammonia or other suitable developer, and the lower chamber receiving the developed copies and being connected to a blower for producing a suction through the same to clean the developed copies from remaining developer so that the copies can be taken out in a clean state.

The invention has for its object to create an improved apparatus of said type in which the developer is by expedient means prevented from passing out from the apparatus into the surrounding space when the apparatus is opened for introducing or taking out the copies.

This and other objects will be obtained by the combination of features as appearing from the following description of a developing apparatus according to the invention, by way of example illustrated in the accompanying drawing, in which:

Fig. 1 is a side elevation of the apparatus, partly in a central vertical section; and Fig. 1A shows a modification.

Fig. 2 is a corresponding transversal section.

In the drawing, reference numeral 1 indicates the casing of the apparatus, made as a box or cabinet. By means of the partition 2 the casing is divided in an upper chamber 3 and a lower chamber 4. The upper chamber 3 is the developing chamber proper, containing a bath 5 of an agent generating a gaseous developer; for instance ammonia.

In the front wall of the casing the upper chamber has an entrance opening 6 for introducing the exposed copies which are to be developed in said chamber. Said opening is normally closed by a cover 7, preferably made as a sliding shutter, held by friction against the casing or by other suitable means (not illustrated) in its upper position. When an exposed copy is to be introduced into the upper chamber, the cover 7 is drawn downwards by means of the handle 15, and then the opening 6 is again closed. A longitudinal vertical wall consisting of wire network or the like may be provided in the upper chamber for preventing the copies from a direct contact with the bath.

The copies developed in the upper chamber, are supplied to the lower chamber through an opening 8 provided in the partition 2. Said opening is normally closed by a rockable flap 9, as shown by solid lines in Fig. 2, but when desired said flap can be turned downwards by an external handle on the shaft of the flap to the open position indicated by dotted lines in Fig. 2, thereby allowing a developed copy passing downwards into the lower chamber, sliding upon said flap. The lower chamber has a take-out opening 10 for the ready copies, provided in the front wall, and a suction opening 11 provided in the rear wall and associated with a blower 12 for producing a suction through the lower chamber. The take-out opening 10 is provided with a cover 13, preferably made as a sliding shutter with a handle 16 and being normally held in open position, as shown in Fig. 1, by the action of suitable means (not illustrated) which in the embodiment illustrated is supposed to be frictional engagement with the casing. As the opening 10 is normally open, the copies falling downwards into the lower chamber will quickly be cleaned from developer remaining on the copies, such developer being carried away by the suction caused by the blower and flowing out through the outlet opening 11 which communicates with the atmosphere through a hose

2

or other conduit (not shown). The opening 10 is provided near the bottom of the lower chamber and at least one additional aperture, such as a horizontal slot 14, is disposed in the front wall of the casing near the entrance opening of the upper chamber. Said aperture or slot extends preferably over the entire lateral dimension of the casing, and the object of the same will appear from the following description of the manner of action.

When a copy has been exposed in a light-tracing apparatus (not shown) it is to be introduced into the upper chamber 3 for development. To allow said copy to be introduced the shutter 7 is drawn downwards by means of its handle 15. By this the shutter 7 uncovers the slot 14 normally closed by the same, so that already in the beginning of the opening movement of the shutter 7 the blower 12 will cause a suction to take place from the external front side of the entrance opening 6 through the slot 14. The effect of this suction is that no gaseous ammonia passing through the entrance opening can reach the space surrounding the apparatus. The suction action existing in front of the entrance opening 6 is increased according to the progressive opening of the shutter 7, as this shutter when moving downwards engages the upper edge of the lower shutter 13 and thereby pushes the shutter 13 downwards so that the take-out opening 10 is progressively closed in dependence upon the opening movement of the upper shutter. When the copy has been introduced into the upper chamber the upper shutter 7 is closed, this preferably being effected by pushing the shutter 13 upwards by means of the handle 16, the take-out opening 10 being simultaneously uncovered. When the copy has been developed the flap 9 is swung downwards into open position, allowing the copy to fall downwards into the lower chamber, and then the flap 9 is immediately closed. In the lower chamber the copy is cleaned from remaining ammonia which disappears through the outlet opening 11, and then the ready copy is taken out through the opening 10.

As will appear from Fig. 1A the slot 14' can be disposed also in the intermediate horizontal wall 9', close to the entrance opening 6', said slot then being controlled by a horizontal extension from the cover 7'. In this modification the two covers are independent of each other and the cover 13' which could be mounted on a vertical pivot, being used only when the apparatus is not in use. In other respects the manner of action is the same as already described.

The frictional engagement of the sliding covers with the front wall can be secured for instance by flat springs (not illustrated) pressing the covers against the wall.

The invention is not restricted to the embodiment as illustrated and described but can be realized in many other ways without departing from the spirit of the invention.

What I claim is:

1. An apparatus for developing copies as exposed, comprising in combination, walls forming a casing having two chambers one above the other, the upper chamber being provided with an entrance opening for introducing copies to be developed by the action of a developer contained within said upper chamber, one of said walls constituting a partition between said two chambers and being provided with an opening for passing copies as developed from the upper chamber to the lower chamber, said lower chamber being provided with a take-out opening for the copies one of the walls of the lower chamber having an additional aperture located near the entrance opening of the upper chamber, suction means for producing a draft through the lower chamber in the direction from the take-out opening to clean remaining developer from the developed copies, a displaceable cover for the entrance opening which cover when in one position closes both the entrance opening and said additional aperture and which when in another position uncovers the entrance opening and unseals said additional aperture to provide communication with the upper chamber to create a draft in the proximity of the entrance opening and thereby to prevent the developer from passing through said entrance opening into the surrounding space.

2. An apparatus for developing copies as exposed, comprising, in combination, walls forming a casing, one of

said walls dividing said casing into to chambers, one above the other, the upper chamber being provided with an entrance opening for introducing copies to be developed by the action of a developer contained within said upper chamber, said wall being provided with an opening for passing copies as developed from the upper chamber to the lower chamber, said lower chamber being provided with a take-out opening for the copies and with at least one additional aperture in a casing wall constituting the front of the lower chamber and located near the entrance opening of the upper chamber, suction means for producing a draft through the lower chamber in a direction from the take-out opening to clean the developed copies from remaining developer, a cover for the entrance opening for closing the same when in normal position but being displaceable for uncovering the same, said cover also closing said additional aperture when in normal position and sealing said additional aperture when displaced and providing communication between it and the upper chamber, a cover for the take-out opening for closing the same in dependence upon the displacement of the first-mentioned cover from its closed position to its open position.

3. An apparatus as claimed in claim 2, wherein the

10

entrance opening is disposed above the take-out opening in one and the same vertical wall of the casing, and the two covers are sliding shutters, the upper one of said shutters, when moved in the direction of uncovering the entrance opening and the additional aperture also operating the lower one of said two shutters to closing position.

4. An apparatus as claimed in claim 2, wherein a rockable flap is provided for controlling the copy-passing opening in the partition and for guiding the copies passing downwards to the lower chamber when in open position.

5. An apparatus as claimed in claim 1, wherein said additional aperture is disposed in the intermediate partition wall, close to the entrance opening.
